KNITTING MACHINES

Filed May 24, 1935

2 Sheets-Sheet 1

This technical drawing illustrates a mechanical assembly, likely a valve or actuator, featuring several key components labeled with numbers:

- 11: A cylindrical component on the left.
- 12: A vertical rod or shaft extending downwards.
- 13: A horizontal rod or shaft extending to the right.
- 14: A bracket or support structure at the top.
- 15: A central vertical rod.
- 16: A horizontal rod extending from the central assembly.
- 17: A vertical rod extending downwards from the central assembly.
- 18: A horizontal rod extending from the central assembly.
- 19: A vertical rod extending downwards from the central assembly.
- 20: A horizontal rod extending from the central assembly.
- 21: A vertical rod extending downwards from the central assembly.
- 22: A cylindrical component on the right.
- 23: A horizontal rod extending from the central assembly.
- 24: A bracket or support structure on the left.
- 25: A horizontal rod extending from the central assembly.
- 26: A vertical rod extending downwards from the bottom assembly.
- 27: A horizontal rod extending from the bottom assembly.
- 28: A vertical rod extending downwards from the bottom assembly.
- 29: A horizontal rod extending from the bottom assembly.
- 30: A vertical rod extending downwards from the bottom assembly.

KNITTING MACHINE

John Vincent Bradley, Wharton, N. J.

Application May 24, 1935, Serial No. 23,291

17 Claims.

(Cl. 66—82)

The present invention relates to full fashioned knitting machines, particularly to knitting machines of this type which include a plurality of individual needle bars, all operated from a common source of power and each of which cooperates with other portions of the machine in knitting a single strip of fabric, co-extensive in width with the needle bar.

Knitting machines of this general type have long been known and many have been and are now in use, such machines embodying occasionally as many as twenty-eight knitting sections, each section including its own needle bar and associated mechanism, and all of the needle bars being operated from a common power driven shaft. Each needle bar has mounted thereon a large number of relatively fragile needles, spaced closely together and in parallelism, as is well-known, and for perfect knitting, all needles of any single needle bar must be intact and in proper positions.

It frequently happens, however, that for some cause or other the needles of some one or more of the battery of needle bars of a single knitting machine may become disarranged or broken thus making it necessary to halt the operation of the machine for the purpose of effecting repairs. The needles of only one needle bar may need such repairs but nevertheless the entire machine must be stopped, in accordance with present practice, in order to halt the motion of the single needle bar upon which work must be done, since all needle bars are driven from a common shaft or source of power. To effect repairs to one set of needles, therefore, the knitting operations of sometimes as many as twenty-seven additional needle bars, all in perfect condition, must be temporarily interrupted. This results in great loss of time and decrease in production of the entire machine.

The present invention contemplates a novel and improved needle bar actuating mechanism which enables the operator of a knitting machine employing a plurality of such needle bars, all actuated from a common source of power, to disconnect from the source of power any needle bar which may actually need repair, allowing the remaining perfect needle bars to continue to operate. When repairs to the defective needle bar have been completed it may be again connected to the common needle bar operating mechanism and will thereafter continue to operate as before. The invention likewise includes certain novel features of construction whereby the operator is enabled to more accurately position or adjust each needle bar with relation to the usual parts of the knitting machine which cooperate with the needle bar and needles in performing the knitting operations. It will be appreciated that the needles must be positioned

with great accuracy so that they move through exactly pre-determined paths in the performance of knitting operations. Other novel features of the invention will be apparent to those skilled in the art.

One embodiment of the invention is illustrated by way of example in the accompanying drawings and will be hereinafter described in detail.

In the drawings:

Figure 1 is a side elevation of portion of a knitting machine showing a needle bar and its operating mechanism, the operating shafts being shown in section;

Figure 2 is a front elevation of the same;

Figure 3 is a top plan view of this mechanism;

Figure 4 is a section on line 4—4 of Figure 3;

Figure 5 is a section on line 5—5 of Figure 3;

Figure 6 is a similar section but showing one of the parts in a different position; and

Figure 7 is a side elevation of portion of the mechanism, showing details.

The frame of the machine is shown only in part and the means for driving the operating parts is not illustrated. It will be understood that the needle bar illustrated, and its operating mechanism, comprises only one knitting unit of a knitting machine embodying a plurality of such units, all driven from a common source of power which may be for instance an electrical motor located at one end of the machine. The various elements which cooperate with the needle bar in performing knitting operations are likewise not illustrated, as these elements are of conventional form and comprise no portion of the present invention.

A small portion of the frame of the machine, which may be designated the table, is indicated at 10, this table extending longitudinally of the machine and being located just above the needle bar operating shafts. The needle bar rock shaft is indicated at 11 and it will be understood that this is a relatively long shaft mounted in suitable bearings for rocking movement and to which the needle bars are individually connected at spaced intervals along the shaft. A second rock shaft, 45 which may be designated a press shaft, is indicated at 12, and this shaft is also suitably supported for rocking movement and lies just below the needle bar rock shaft. The needle bar itself is indicated at 13 and it will be understood that this bar, from which project the needles 14, is also of conventional design insofar as its details of construction are concerned.

The needle bar arm is indicated at 15 and one end of this arm is provided with an enlarged portion 16 having a cylindrical aperture therein through which the needle bar rock shaft 11 projects, there being no positive connection between arm and shaft at this point, the shaft 11 and bearing 16 being freely rotatable relatively to each 60

other. At its outer end the needle bar arm has rigidly secured thereto a cross bar 17 having cylindrically formed end portions 18. Upon each of these cylindrical portions 18 of the cross bar 17 is mounted, respectively, a bracket 19 formed as a clamping bracket in that it is split as shown in Figure 1 and the parallel portions 20 thereof being provided with interiorly threaded aligned apertures through which clamping screw 21 projects.

The outer ends of clamping brackets 19 lie between downwardly projecting spaced lugs 22 of needle bar supporting brackets 23 and hinge pins 24 project through aligned apertures in lugs 22 and clamping brackets 19, these hinge pins being detachably secured in position by retaining screws 25. The needle bar is thus supported for rocking movement about the common axis of hinge pins 24. Projecting downwardly from the needle bar assembly is the needle bar rocking lever 26 and the lower end of this lever 26 is connected by means of a link 27 to a press arm 28 mounted upon the press shaft 12 so as to rock with that shaft. Arm 28 may be angularly adjusted with respect to shaft 12 when the clamp screw 29 is loosened and thereafter tightly secured upon the shaft by tightening the clamping screw. Link 27 is pivotally connected at 30 to lever 26 and is provided with a plurality of notches 31 any one of which may be engaged with a pin 32 fixed upon press arm 28 so that the needle bar lever 26 and the needle bar itself may be caused to occupy different angular relationships with the vertical by shifting pin 32 from notch to notch.

Toward the end of the press link 27 remote from pivot 30 are a plurality of hooks 33 either one of which may be caused to engage a short horizontal bar 34 rigidly secured to the lower end of a bracket member 35 depending from the table 10. By lifting the press link 27 so that one of the hooks 33 operatively engages the supporting bar 34, the needle bar may be disengaged from the oscillating press shaft 12, as will be apparent.

Fixed upon needle bar rock shaft 11, as by means of pins 11' and upon opposite sides of the needle bar arm 15, respectively, are rocker arms 40 and 41, these arms extending toward the cross bar 17 mounted upon the outer end of the needle bar arm 15 and the outer ends of rocker arms 40 and 41 being flattened as shown most clearly in Figures 5 and 6 and lying parallel and closely adjacent the vertical side faces of the needle bar arm 15. Secured to the lower edges of the ends of rockers 40 and 41 is a bridging or connecting member 42 and pivotally connected to member 41, as by means of a pivot pin 43 is a swinging latch member 44 which may be moved from the position in which it is shown in Figure 5, in which its free end is retained within a notch formed in rocker arm 40, to the position in which it is shown in Figure 6, in which its free end is remote from rocker arm 40. Latch member 44 is provided with an adjustable securing screw 45 and bridging plate 42 has a similar adjustable securing screw 46, provided with a locking nut 47. When the latch member 44 is in the position in which it is illustrated in Figure 5, the lower end of securing screw 45 engages the needle bar arm 15, being received within a notch 48 formed in the upper surface of that arm, and the upper end of supporting screw 46 engages the under surface of the needle bar arm.

By the means just described, therefore, the rocker arms 40 and 41 may be connected to or

disconnected from the needle bar arm and likewise the angular relationship of the needle bar arms and rocker arms may be changed within limits by manipulating the securing and adjusting screws 45 and 46. It will be apparent by this arrangement that the needle bar may be operatively connected to or disconnected from the needle bar rock shaft 11 as desired, and also that its angular relationship to the needle bar rock shaft may be adjusted.

Extending upwardly from the needle bar arm 15 at about its mid-point is a hanger 50, this hanger being formed in three portions, as most clearly shown in Figure 7, a lower bracket-like portion 51 secured to the needle bar arm in any suitable manner, as by means of machine screws 52; an intermediate portion 53 pivotally connected to the lower portion 51, as by a pivot member 54; and an upper portion 55 connected to the intermediate portion 53 for a limited longitudinal adjustment relatively thereto, as by means of screw bolts 56 which extend through circular apertures formed in one of these members and elongated slots formed in the other.

Toward its upper end, part 55 is provided with a circular aperture 55'. Slidably mounted upon a bracket 57 secured to table 10 is a latching pin or locking pin 58, one end of which is adapted to pass through aperture 55' in the hanger 50 and the other end of which is provided with a curved portion 59 which may be caused to rest in either one or the other of notches 60 formed in a plate 61 secured to bracket 57, and to be thereby locked against longitudinal movement. It is the function of the hanger 50 and locking pin 58 to transmit the weight of the needle bar arm 15 and the needle bar assembly to the table portion 10 of the frame when the needle bar arm is disconnected from rocker arms 40 and 41, the needle bar being thereby itself supported from the frame and remaining stationary while the rocker arms 40 and 41 may continue to oscillate with the needle bar rock shaft 11.

For supporting the needle arm 15 against longitudinal sliding movements on the needle bar rock shaft 11 screws 65 are provided, these screws extending respectively through aligned, interiorly threaded apertures formed in rocker arms 40 and 41, the heads 66 of the screws bearing against vertical side faces formed on the needle bar arm and the screws being likewise provided with locking nuts 67. The screw heads therefore comprise abutment members preventing longitudinal movement of the needle bar arm upon shaft 11 and also constitute means for effecting longitudinal adjustment of the needle bar and needle bar arm axially of this shaft, since by manipulating screws 65 the needle bar arm may be longitudinally shifted and thereafter locked in such shifted position.

In the normal operation of the mechanism just described the needle bar arm 15 will be operatively connected to the rocker arms 40 and 41, the latching member 44 occupying the position in which it is shown in Figure 5, and the supporting and adjusting screws 45 and 46 having their inner ends tightly engaging the upper and lower surfaces of the needle bar arm as shown in this figure. Assuming that it becomes apparent that the needles have become broken or disarranged so that the product being produced is imperfect, and hence that it is necessary to halt the operations of this particular needle bar for the purpose of inspection and repair, the first step of the operator will be to stop

the entire machine. This stopping will be effected in such manner that when the parts finally come to rest, the needle bar arm 15 will be in its highest or uppermost position. As soon as the parts have become stationary, the securing screw 45 is backed out to the position in which it is shown in Figure 6 and the latching member 44 swung laterally into the position in which it is shown in this figure. The needle bar arm may then be slightly raised until the aperture 55 in the hanger 50 is in line with the end of the latching member or locking pin 58 and the locking pin is then slid longitudinally in its bearings so as to pass through this aperture, the end 59 of the locking pin being then depressed into the notch 60 which lies nearest the hanger 50 so that the pin is locked in this position. The weight of the needle bar and needle bar arm is therefore transmitted to the platform 10 through the hanger. Next the press link 27 is lifted and the pin 32 disengaged thereby, one or the other of the hooks 33 being caught upon the suspending bar 34. The needle bar operating lever 26 is therefore disconnected from the press shaft 12. After this has been done, the needle bar is wholly disconnected from both operating shafts 11 and 12 and the machine may then be started so that the remaining needle bars may continue to function while the needle bar needing repair will remain stationary. Repairs may therefore be conveniently made without materially decreasing the production of the machine as an entirety. After the needle bar has been placed in proper condition for operation the entire machine will again be stopped, the locking pin 58 operated to release the hanger 50, and the needle bar arm 15 again operatively connected to the rocking levers 40 and 41 by actuation of the latch member 44 and the securing screw 45. The entire machine may then be started.

By the mechanism just described great saving in operating time for a machine having a plurality of individually operating needle bars will be realized. Furthermore the advantages of very fine and accurate adjustability will also be realized. As has been before explained the needle bar arm 15 may be moved axially of the shaft 11 and retained accurately in any desired position of adjustment. Likewise its angular position relative to this shaft may be accurately adjusted. Again the needle bar itself may be very accurately adjusted to truly horizontal position by manipulation of the clamping brackets 19.

In adapting the invention to knitting machines of different types and the details of which vary considerably in design, the arrangement and design of the component elements of the invention may be considerably varied without departing from the teaching thereof, as will be apparent to one skilled in the art.

As it is occasionally necessary or desirable to halt the operation of one needle bar arm in a knitting machine for an appreciable length of time, sometimes for a comparatively lengthy period, it is necessary to provide means to pass lubricant to the contacting cylindrical bearing surfaces of shaft 11 and needle bar arm bearing 16. The shaft 11 fits snugly within the bearing 16 and, as previously set forth, continues to oscillate when the needle bar arm is disconnected. Therefore oil ducts 16' are formed in bearing member 16 and from time to time lubricant is

passed through these ducts to the bearing surfaces mentioned to prevent wear.

Having thus described the invention, what is claimed as new and desired to be secured by Letters Patent is:

1. A full fashioned knitting machine comprising a rock shaft and a plurality of knitting units to be simultaneously operated by said rock shaft, each such unit including, a needle bar arm having one end rotatably mounted on said shaft and carrying a needle bar, a rocker arm fixed upon said rock shaft at a point adjacent the needle bar arm, and means for operatively connecting and disconnecting said needle bar arm and said rocker arm, said means including an adjustment device whereby the angular relationship of the arms may be varied, and said connecting means including members cooperative to insure reconnection of said arms in the same relationship that existed prior to their disconnection. 20

2. A full fashioned knitting machine comprising a rock shaft and a plurality of knitting units to be simultaneously operated by said rock shaft, each such unit including, a needle bar arm having one end rotatably mounted on said shaft and carrying a needle bar, two rocker arms fixed on said shaft, one on each side of said needle bar arm, and means detachably connecting said rocker arms and needle bar arm, said means including members cooperative to insure reconnection 30 of said arms in the same relationship that existed prior to their disconnection.

3. A full fashioned knitting machine comprising a rock shaft and a plurality of knitting units to be simultaneously operated by said rock shaft, each such unit including, a needle bar arm having one end rotatably mounted on said shaft and carrying a needle bar, two rocker arms fixed on said shaft, one on each side of said needle bar arm, and means detachably connecting said rocker arms and needle bar arm, said means including a swinging latch member pivotally connected to one of said rocker arms and adapted to project within a recess formed in the other rocker arm. 40

4. A full fashioned knitting machine comprising a rock shaft and a plurality of knitting units to be simultaneously operated by said rock shaft, each such unit including, a needle bar arm having one end rotatably mounted on said shaft and carrying a needle bar, two rocker arms fixed on said shaft, one on each side of said needle bar arm, and means detachably connecting said rocker arms and needle bar arm, said means including two spaced cross members extending from one rocker arm to the other, one of said members being fixed and the other comprising a swinging latch member, the needle bar arm lying between said cross members and being retained thereby when said swinging latch member is in latching position. 55

5. The combination set forth in claim 4 in which the said cross members are provided, respectively, with adjusting means contacting with the needle bar arm whereby the angular relationship of the needle bar arm may be varied with respect to the rocker arms. 65

6. A full fashioned knitting machine comprising a rock shaft and a plurality of knitting units to be simultaneously operated by said rock shaft, each such unit including, a needle bar arm having a needle bar mounted thereon, means for operatively connecting said needle bar arm to said rock shaft or disconnecting it therefrom, said means including members cooperative to insure 70 75

reconnection of said arm to said shaft in the same relationship that existed prior to their disconnection, a frame part above said needle bar arm, and means for connecting the needle bar arm to the frame part when said arm is disconnected from said shaft.

7. A full fashioned knitting machine comprising a rock shaft and a plurality of knitting units to be simultaneously operated by said rock shaft, 10 each such unit including, a needle bar arm having a needle bar mounted thereon, means for operatively connecting said needle bar arm to said rock shaft or disconnecting it therefrom, said means including members cooperative to insure reconnection of said arm to said shaft in the same relationship that existed prior to their disconnection, a frame part above said needle bar arm, and means for connecting the needle bar arm to the frame part when said arm is disconnected 15 from said shaft, said means including a hanger member attached to said arm and extending upwardly therefrom, and a latch member mounted on the frame for detachably engaging the hanger member.

20 8. A full fashioned knitting machine comprising a rock shaft and a plurality of knitting units to be simultaneously operated by said rock shaft, each such unit including, a needle bar arm having a needle bar mounted thereon, means for operatively connecting said needle bar arm to said rock shaft or disconnecting it therefrom, a frame part above said needle bar arm, and means for connecting the needle bar arm to the frame part when said arm is disconnected from 25 said shaft, said means including a hanger member attached to said arm and extending upwardly therefrom, said member being apertured at its upper end, and a locking pin slidably mounted on the frame part and adapted to be projected within said aperture or removed therefrom.

30 9. A full fashioned knitting machine comprising two rock shafts and a plurality of knitting units to be simultaneously operated by said rock shaft, each such unit including, a needle bar, and means 35 connecting said needle bar to both of said shafts whereby it is supported and operated, said means being disconnectible so that the needle bar may remain stationary when the shafts are in operation, and said means including members cooperative to insure reconnection of said needle bar to said shafts in the same relationship that existed prior to its disconnection therefrom.

40 10. A full fashioned knitting machine comprising a frame and a plurality of knitting units 45 to be simultaneously operated by said rock shaft, each such unit including, a needle bar, means for vertically reciprocating the needle bar, and means for rocking the needle bar about a horizontal axis, said last mentioned means including a rock 50 shaft having an arm and a link connecting said arm and needle bar, said link being detachable from said arm, and means for supporting the link from the frame when disconnected from said arm.

55 11. A full fashioned knitting machine comprising a rock shaft, a needle bar arm rotatably mounted on said shaft and carrying a needle bar, and means for connecting said arm to said shaft for movement therewith, said means including threaded elements disposed substantially parallel 60 to the shaft for adjusting the position of the needle bar arm longitudinally along the shaft.

65 12. A full fashioned knitting machine comprising a rock shaft, a needle bar arm adapted to be oscillated thereby, said arm having a cross bar 70 at the end remote from said shaft, brackets

75 mounted upon the ends of said cross bar and adjustable circumferentially about the longitudinal axis of said bar, means for locking said brackets in fixed adjustment on said cross bar and a needle bar pivotally mounted on said 80 brackets.

13. A full fashioned knitting machine comprising an elongated rock shaft and a plurality of knitting units to be simultaneously operated by said rock shaft, each such unit including a needle bar, and means for normally transmitting rocking movements of the shaft to the bar for knitting purposes, said means comprising a rocker arm secured to said rock shaft, a needle bar arm secured to said needle bar and readily disconnectible means for securing said needle bar arm to said rocker arm, said last named means including members cooperative to insure reconnection of said needle bar arm and said rocker arm in the same relationship that existed prior to their 15 disconnection.

14. A full fashioned knitting machine comprising a rock shaft and a plurality of knitting units to be simultaneously operated by said rock shaft, each such unit including a needle bar arm having a needle bar mounted thereon, and readily operable latching means for operatively connecting said arm to said shaft or disconnecting the same therefrom, as desired, whereby any such unit may be rendered inactive while the other 25 units remain positively connected to the rock shaft, said latching means including members cooperative to insure reconnection of said arm to said shaft in the same relationship that existed prior to its disconnection therefrom.

30 15. A full fashioned knitting machine comprising a frame, a rock shaft and a plurality of knitting units to be simultaneously operated by said rock shaft, each such unit including a needle bar arm having a needle bar mounted thereon, means 35 for operatively connecting said arm to said shaft or disconnecting the same therefrom, said means including members cooperative to insure reconnection of said arm to said shaft in the same relationship that existed prior to their disconnection and means for connecting the arm and frame when the arm and shaft are operatively disconnected.

40 16. A full fashioned knitting machine comprising a rock shaft and a plurality of knitting units to be simultaneously operated by said rock shaft, each such unit including a needle bar arm rotatably mounted on said shaft and carrying a needle bar, and means for connecting said arm to said shaft for movement therewith, said connection being effected at a point remote from said shaft, said connecting means including members cooperative to insure reconnection of said arm to said shaft in the same relationship that existed prior to their disconnection.

45 17. A full fashioned knitting machine comprising a rock shaft and a plurality of knitting units to be simultaneously operated by said rock shaft, each such unit including a needle bar arm having one end rotatably mounted on said shaft and 50 carrying a needle bar, a rocker arm fixed upon said rock shaft at a point adjacent the needle bar arm, and means for connecting and disconnecting said arms, whereby the motion of any needle bar may be halted without halting the remaining needle bars, said means including members cooperative to insure reconnection of said arms in the same relationship that existed prior to their disconnection.
